LIPSTICK HOLDER AND THE LIKE

Edward Noyack, Seymour, Conn., assignor to The Risdon Manufacturing Company, Naugatuck, Conn., a corporation of Connecticut

Application October 5, 1950, Serial No. 188,575

4 Claims. (Cl. 206—56)

1

This invention relates to holders for lipsticks and the like of the kind adapted to project the stick from the holder, and retract it again, by rotary motion. It relates particularly to those rotary holders which have the propelling and retracting mechanism disposed beneath the stick. Such holders can be of rather small diameter relative to the diameter of the stick and, accordingly, can be made rather long relative to their diameter without being cumbersome. The 10 holders can be used for sticks other than lipsticks of course, as well as for lipsticks, but since they are used principally for lipsticks at present, they are referred to hereafter for brevity, substantially only as lipstick holders.

Speaking generally, a lipstick holder of the type indicated consists principally of a cylindrical outer shell which is open at its upper end for projection of the stick, an elevator within the outer shell to carry the stick, an elongated threaded member attached to and projecting below the elevator, and a complementary member threaded to the elongated member as it were so that rotation of another shell or a finger piece, while the outer shell is held stationary, reciprocates the elongated member and elevator. Usually in practice heretofore, the elongated member has had the form of a twisted bar, the twists providing its threading, or the form of a flat bar serrated at its edges, the serrations acting as a thread. Occasionally such devices fail to operate smoothly, perhaps due to the rather crude form of thread or to the small area of contact between the bar and the complementary member. Also it has been proposed heretofore to make the elongated and complementary members in the form of convoluted tubes or shells. This provides a rather large area of contact between the two members, but the convoluted-tube holders heretofore proposed have not been well suited for large scale production under factory conditions.

The present invention substantially eliminates the foregoing difficulties of holders in which the elongated member is in the form of a twisted bar or serrated bar, by employing convoluted tubes or shells, but it does so in such a manner that the holder can be made on a large scale and cheaply. Briefly, to this end, the holder has an outer shell, an elevator reciprocatable in the outer shell to project and retract the stick, an operating member at the lower portion of the holder and which is rotatable relative to the shell containing the elevator, and two convoluted tubes below the elevator, one within the other

2

with their convolutions inter-engaging, one being connected to the elevator, and one being connected non-rotatably to the elevator-containing outer shell and the other connected non-rotatably to the operating member. At least preferably, either the outer shell or the operating member, or each of them, is cylindrical in form and encloses and lies close to the outer of the convoluted tubes to give those tubes side-wise support as they may need. Preferably the elevator is mounted non-rotatably relative to the outer shell, and preferably by the use of a pierced diaphragm or the like within the outer shell. Preferably also the operating member is connected to both the outer shell and one of the convoluted tubes by a single connection. These and other matters of the invention appear in the lipstick holder shown in the accompanying drawing and described hereafter.

20 It will be noted that wherever the words up or down or the like are used herein, "up" and the like indicate the direction toward the end of the holder from which the lipstick is protruded for use, and "down" and the like indicate the opposite directions.

In the accompanying drawings Fig. 1 is a sectional elevation of a lipstick holder embodying the invention. Fig. 2 is a cross section on line II—II of Fig. 1. Fig. 3 is a perspective view of the elongated member of the holder of Fig. 1 and the convoluted tube which is attached to it.

The outer portion of the holder illustrated comprises two members, one of which consists of a cylindrical tubular shell 1 and an auxiliary cylindrical tubular shell 2, and the other of which comprises the finger piece 3 which constitutes the operating member in the present instance. The auxiliary tubular shell 2 is of a slightly smaller diameter than the shell 1, is open at its upper end, and at its lower end has a diaphragm 4 pierced with a non-circular hole 5. The lower end of the auxiliary shell 2 is set friction tight into the open upper end of the shell 1; it can be provided with external projections if desired, such as circumferential ribs 6 for example, to hold it rotationally and longitudinally stationary with respect to the shell 1. The lower end of the shell 1 is provided with an in-turned flange 7. The construction of this outer shell from two parts 1 and 2 is primarily a matter of convenience, i. e. mostly as a ready means for providing the outer shell with the diaphragm 4 and a shoulder 8 to act as a stop for the cap 9 of the holder. As is conventional, the upper portion of the outer shell may be provided with a

projection 10 to frictionally, but releasably, secure the cap 9 on the holder when the latter is not in use. The elevator 11 which holds the stick, e. g. a lipstick, is located within the upper portion of the outer shell, i. e. above the diaphragm 4, and is reciprocatable within this shell so that it can be moved to either project the stick from the opening at the upper end of the outer shell when the stick is to be used, or retract the stick into the outer shell for protection when not in use.

Within the lower portion 1 of the outer shell and below the diaphragm 4 a convoluted tube 12 is placed. This tube 12 is slightly smaller in diameter, externally, than the interior of the outer shell and thus fits loosely therein throughout its entire length, but at the same time the outer shell can give the tube 12 any sidewise support it may need to keep it substantially centered along the center line of the holder. The lower end of the tube 12 rests on the inside of the internal flange 7 of the outer shell. The finger piece 3 rests against the outer side of this flange 7 of the lower portion 1 of the outer shell, i. e. bears against this flange at the side opposite the convoluted tube 12. The finger piece is fixedly connected to the convoluted tube 12 by a central portion 15 of the finger piece which is extended up through the opening 16 of the flange 7; for this purpose if desired, the lower end of the tube 12 can be provided with an internal flange 17 pierced with a hole 18 a little smaller than the opening 16, and the central portion 15 of the finger piece 3 can be wrapped or broken down around the inner edge of the flange 17 thus exposed. The riser 15 rotates freely within the opening 16. Accordingly, when the finger piece is rotated, with respect to 1-2, the convoluted tube 12 rotates with it. If desired, a plug, e. g. a thin disc 21, can be inserted in the hole left by forming the riser 15, to close this hole for finish.

The elevator 11 is mounted on the upper end of a bar 20 which extends through, and is reciprocatable within, the non-circular hole 5 in the diaphragm 4 of the upper part 2 of the outer shell, and is correspondingly non-circular. Thus the elongated bar 20 may be of flat stock and the hole 5 a slot, as before indicated. At its other end the elongated bar 20 is attached non-rotatably to a short convoluted tube 23 which is located within the convoluted tube 12. The convolutions of the tube 23 are complementary to the convolutions of the tube 12, and the two are interthreaded or intermeshed. Accordingly, when the outer tube 12 is rotated and the tube 23 is held against rotation, one tube will move lengthwise of the other.

In operation, the cap 9 is first removed of course. The finger piece 3 then is rotated by one hand while the other hand holds the outer shell 1-2 to prevent rotation of the outer shell. The rotation of the finger piece 3 rotates the convoluted tube 12 through the riser 15. However the diaphragm 4 of the outer shell, because of the non-circular opening 5 and the corresponding non-circular form of the bar 20, prevents rotation of the cooperating convoluted tube 23. Accordingly the tube 23 moves lengthwise of the tube 12 and thus raises the elevator 11 and projects the stick. To lower the stick again, the

finger piece 3 is rotated in the opposite direction.

The diaphragm 4 with the hole 5 and the flat bar 20 may be replaced by, e. g., the more conventional pin on the elevator 11 projecting into a longitudinal slot. However, I prefer the arrangement illustrated for constructional reasons. Also the operating member need not be a short finger piece like the finger piece 3. If desired it can be a longer member of course. In these and other respects it is to be understood that my invention is not limited to the details of construction and operation described above in the specification and shown in the drawings, except as appears hereafter in the claims, and that these claims are to include equivalents of the elements mentioned in them as well as those elements themselves.

I claim:

1. In a holder for sticks, an outer shell having an opening at both ends and an internal projection at its lower end, a diaphragm located between the ends of and within the outer shell and having a non-circular opening through it, an elevator within the outer shell between the diaphragm and the upper end of said shell and movable longitudinally from a projected to a retracted position and vice versa, a convoluted tube within the outer shell between the diaphragm and the lower end of said shell, rotatable therein and resting on the internal projection of the lower end of the outer shell, a second tube with convolutions disposed within the first mentioned tube and with its convolutions inter-engaging with the convolutions of the first mentioned tube, an elongated carrier passing through the opening in the diaphragm and non-circular in section to prevent rotation therein, attached at its upper end to the elevator and at its lower end attached to the second convoluted tube, and an operating member extending into the lower end of the outer shell and attached to the lower end of the first mentioned tube and bearing against said internal projection of the outer shell at the opposite side of said projection from said first mentioned tube.

2. The subject matter of claim 1, characterized by the fact that the external diameter of the protruding surface of the convolutions of the first mentioned tube is only slightly smaller than the internal diameter of the outer shell between the diaphragm and lower end of the outer shell.

3. The subject matter of claim 2, characterized by the fact that the elevator carrier is a flat bar and the opening in the diaphragm is a slot.

4. The subject matter of claim 3, characterized by the fact that the second convoluted tube is of a short length relative to the length of the first mentioned tube.

EDWARD NOYACK.
